UNITED STATES PATENT OFFICE

2,167,223

SEPARABLE CONNECTOR

Nils A. Tornblom, Chicago, Ill., assignor to Appleton Electric Company, a corporation of Illinois

Application September 21, 1936, Serial No. 101,713

1 Claim. (Cl. 173—339)

An object of the present invention is to produce a simplified and improved separable connector of the dead end type; another object being to provide means for quickly and easily securing the receptacle member of such a connector to a wall or cover in which it is desired to mount the same.

The various features of novelty whereby my invention is characterized will hereinafter be pointed out with particularity in the claims; but, for a full understanding of my invention and of its objects and advantages, reference may be had to the following detailed description taken in connection with the accompanying drawing, 15 wherein:

Figure 1 is a rear view of a box cover in which the receptacle member of one of my improved connectors is secured; Fig. 2 is a sectional view taken on line 2—2 of Fig. 1, only the cover element being shown in section while the connector is in elevation; Fig. 3 is a view similar to Fig. 2, showing parts of the connector, as well as the cover element, in section; Fig. 4 is a section on line 2—2 of Fig. 1 through the receptacle member, the cover element and the plug being omitted; Fig. 5 is a sectional view taken on line 5—5 of Fig. 4; Fig. 6 is a section on line 6—6 of Fig. 3; and Fig. 7 is a longitudinal section through the connector on line 7—7 of Fig. 6.

Referring to the drawing, 1 represents a cylindrical block of insulating material against the front end face of which lies a thick disk 2, also of insulating material. The disk 2 is secured to the front end of a rod or shaft 3 that extends rearwardly through the center of the part 1. The rear end of the rod or shaft is reduced in diameter; the reduced part extending through a washer 4 and being riveted over the latter, as indicated at 5. The washer is of larger diameter than the bore in the block 1 immediately in front of the washer, so that the rod or shaft serves to hold the disk 2 against the front end of the block. A torsion spring 6 surrounds the rod or shaft 3 in an enlarged chamber 7 in the front end of the block. One end of the spring projects laterally into a groove 8 opening out of the side of the chamber 7, while the other or forward end of the spring is bent forwardly, as indicated at 9, and entered into a hole in the disk 2. Consequently, the spring tends to hold the cover in a fixed angular position, but permits it to be turned against the resistance of the spring. The only novelty in the construction so far described lies in the location of the spring, since the block and the disk 2 are substantially the same as the cor-

responding parts in my prior application, Serial Number 72,045, which has matured into Pat. No. 2,114,258, issued April 12, 1938.

As in my aforesaid application, the disk 2 has a plurality of passages 10 extending through the same and adapted in one angular position of the disk to register with longitudinal passages 11 in the block 1. Normally the spring holds the disk in such angular position that the two sets of passages are out of registration with each other and the disk serves as a cover for closing the passages 11 as in the construction disclosed in the aforesaid application.

Within the block 1 are a plurality of tubular contact pieces 12 that are simply inserted from the rear end of the block into passages 13 coaxial with and somewhat larger in diameter than the passages 11. The central portion of the block is made somewhat longer than the portions lying outwardly from the contact pieces 12, so that these contact pieces may be made long enough to reach rearwardly to a little disk 14 of insulating material secured to the rear face of the rearward extension 15 of the block. The rear ends of the contact pieces 12 are thus exposed and may serve as terminals to which wires may be attached. In the arrangement shown, there is a screw 16 entering the side of each of the terminal portions of the contact pieces. It will thus be seen that the contact pieces need not be molded into the block but may simply be dropped into position after the block has been molded, and be held against falling out by the little disk or plate 14.

The unit just described is housed in a cylindrical sheet metal shell 17 somewhat larger in diameter than the external diameter of the block 1 and disk 2. The shell 17 has at its rear end an internal annular flange 18 which may be said to form the bottom of a cup which is cut away so as to leave only a fairly narrow rim or marginal portion. At diametrically opposed points the flange 18 is provided with inwardly directed ears 19 which rest against seats 20 extending in a transverse plane inwardly from the periphery of the block. The ears are secured to the block by means of screws 21 that pass through the ears and into the block. The block as a whole is preferably reduced very slightly in diameter from the plane of the seats 20 rearwardly, whereby there is provided a very narrow ledge or shoulder 22 surrounding the block and facing toward the rear. The flange 18 is thus permitted to rest solidly against an annular face on the block immediately in front of the same, thus assisting

in holding the shell or cup and the block coaxial. The forward end of the shell or cup is flanged outwardly, as indicated at 23. At some distance rearwardly from the flange 23 I punch 5 ears 24 out of the metal of the cylindrical part of the cup or shell. The parts are so proportioned that when the shell is slipped into a hub-like part 25 on a box cover 26 or other wall member, the flange 23 abuts against one end of the hub, while the ears 24 may be bent outwardly 10 past the rear face of the cover or other wall. By cutting notches 27 in the rear side of the cover at the places where the ears are to engage the cover, the ears may be bent into the notches and thus hold the cup or shell against rotation. 15

The plug member 28 may be of any usual or suitable construction, being provided with long parallel contact fingers 29 projecting from one end thereof, the fingers being so arranged that 20 each may enter one of the passages 10 in the cover disk 2 of the receptacle and, after this disk has been turned through the proper angle, may move on through the passages 11 and into the bores of the tubular contact pieces 12. The 25 plug is provided with a tubular extension or skirt 30 somewhat longer than the projecting portions of the contact fingers and thus serving as a guard for the latter. The part 30 is so proportioned that it may be inserted in the shell or cup 17 and surround the block 1 and disk 2. The contact fingers 29 could conceivably be employed as driving members to rotate the disk 2, but there are various reasons why this should not be done. Therefore, as in my aforesaid application, I provide means for positively turning 30 the disk 2 against the resistance of the spring, without imposing any load on the contact fingers. The driving element comprises a rib 31 extending lengthwise of the skirt or sleeve 30 along the inner face of the latter, the rib being shown as being held to the skirt or sleeve by rivets 32. In the periphery of the disk 2 there is a notch 33 extending throughout the thickness of the disk; this notch being of the size and 45 shape to receive the rib 31 when the plug member is applied to the receptacle member. The parts are so positioned that the rib can enter the notch 33 only at a time when the contact fingers 29 are aligned with the passages 10 in the disk. In the periphery of the block 1 there is 50 an L-shaped groove 34 adapted to form with the notch 33 a bayonet slot or groove when the disk is in its normal idle position, as indicated in Fig. 4, at which time it forms a cover for the 55 passages 11 in the block. When the plug is first applied to the receptacle, with the rib 31 entered in the notch 33, the forward movement of the plug is arrested as soon as the rib travels across the width of that part of the groove 34 directly 60 behind the notch 33. Then, upon turning the plug, the rib is carried to the longitudinal section of the groove 34 and, upon pushing the plug inward, the rib moves back into this longitudinal section of the groove, as indicated in Fig. 3, 65 thereby allowing the contact fingers 29 to be operatively engaged with the contact pieces 12.

I prefer that the actual guiding of the plug be accomplished by other means than the rib and the bayonet groove or slot heretofore described. 70 I have therefore formed in the cylindrical wall of the cup or shell 17 a bayonet slot 35 similar to the groove in the block 1 and disk 2 and preferably in registration with the latter at times when the receptacle and the plug are not engaged with each other. Thus, in the arrange-

ment illustrated, the rivets 32 are visible through the long longitudinal leg of the slot 35 in the cup or shell after a connection has been made. The rivet nearest the outer end of the sleeve or skirt 30 is extended radially beyond the periphery of the latter and has fixed thereon a little collar 36 whose diameter is equal to the width of the bayonet slot 35. At the time the rib 31 enters the notch 33 in the disk, the projection 36 on the plug enters the inlet end of the slot 35, which is the right-hand end in Fig. 2. Then, as the plug is pushed in, projection 36 strikes the edge bounding the transverse leg or section of the bayonet slot 35 along the rear, and then the plug must be turned before it can be moved farther in the forward direction. After turning the plug through a predetermined angle, the projection 36 enters the long longitudinal rear leg or section of the slot. Thus the movements of the projection 36 and the corresponding end of the rib 31 are exactly alike; the projection 36 and the slot 35 constituting the guiding means and leaving to the rib 31 simply the duty of turning the disk 2. After the plug and the receptacle have been assembled, the rib 31 still serves to prevent sidewise pressure on the contact fingers, acting as a bar lying within and extending along two registering grooves and thus preventing relative rotary movements of the two parts in which the grooves are located. 30 In other words, the bar is interlocked with the block and therefore acts as a stop or holding device for the disk with which it is also interlocked.

It is usually desirable to provide means for effectively grounding the casing or housing of the plug. In the arrangement shown, there is a window 37 cut into the rear portion of the cylindrical shell 17, and through this window extends a resilient metal contact finger 38 that may conveniently overlie one of the ears 19 and be fastened to the receptacle by the screw 21 that passes through that ear. With this arrangement, when the plug is connected to the receptacle, the contact finger 38 rides on the periphery 45 of the sleeve or skirt 30 and, through the wiping action resulting from this relative movement, remaining clean and thus insuring a good electrically conductive grounding connection for the casing or housing of the plug. 50

It will thus be seen that I have produced a simple and novel separable connector, consisting of a few rugged parts; the construction being such that the part of the plug which is in telescopic relation to the receptacle is wholly surrounded by the receptacle. Consequently, nothing that lies outwardly beyond the cylindrical wall of the receptacle can in any way interfere with the making or interrupting of a connection or with the proper functioning of the device, and the receptacle may be provided with simple means on the exterior thereof for clamping it to a wall which may be a box cover or other type of wall. It will also be seen that while some of the novel features relate particularly to 65 a dead end receptacle, insuring the proper covering of the contacts in the latter when the plug is withdrawn and the uncovering of the contacts to permit the entry of the cooperating fingers in the plug, other of the features are applicable to 70 connectors in general. For example, the cup-shaped casing member in which the insulating plug or body of the receptacle is mounted, may advantageously be employed in connectors of other types. 75

While I have illustrated and described with particularity only a single preferred form of my invention, I do not desire to be limited to the exact structural details thus illustrated and described; but intend to cover all forms and arrangements which come within the definitions of my invention constituting the appended claim.

5 I claim:

In a device of the character described, a cylindrical block of insulating material having a rear portion of reduced diameter to produce a rearwardly facing external shoulder surrounding the block, a sheet metal cup-shaped shell larger in diameter than the block having in the bottom

an opening through which said rear portion of the block extends while the marginal part of the bottom of the shell rests against the shoulder, the bottom of the shell having ears projecting into the opening in the bottom of the shell, the portion of the block of reduced diameter having seats for said ears, an external flange on the front end of said shell, and rearwardly-extending ears struck up from the shell behind said flange to cooperate with the flange to secure the device to a wall through which it extends by clamping such wall between the flange and the ears.
